(57) **CLAIM**

We claim the ornamental design for a seating surface for ride on vehicle, as shown and described.

DESCRIPTION

FIG. 1 is a front right side perspective view of a seating surface for ride on vehicle according to the new design.

FIG. 2 is a left rear side perspective view of the seating surface for ride on vehicle shown in FIG. 1.

FIG. 3 is a right side view of the seating surface for ride on vehicle shown in FIG. 1.

FIG. 4 is a left side view of the seating surface for ride on vehicle shown in FIG. 1.

FIG. 5 is a top plan view of the seating surface for ride on vehicle shown in FIG. 1.

FIG. 6 is a bottom plan view of the seating surface for ride on vehicle shown in FIG. 1.

FIG. 7 is a front view of the seating surface for ride on vehicle shown in FIG. 1; and,

FIG. 8 is a rear view of the seating surface for ride on vehicle shown in FIG. 1.

Features shown in broken lines in the drawings are not part of the claim.
